CLAIM

The ornamental design for a slat wall panel, as shown and described.

DESCRIPTION

FIG. 1 is an isometric view of a slat wall panel showing my new design;

FIG. 2 is an end view thereof;

FIG. 3 is a front elevational view thereof;

FIG. 4 is a back elevational view thereof;

FIG. 5 is a top view thereof; and,

FIG. 6 is a bottom view thereof.

The vertical broken line and the broken lines showing a portion of the slat wall panel in the drawings are included for the purpose of demonstrating that the slat wall panel is of indeterminate length.
